UNITED STATES PATENT OFFICE.

GEORGE E. MOLYNEUX, OF BAYONNE, NEW JERSEY, ASSIGNOR TO THE SINGER
MANUFACTURING COMPANY, A CORPORATION OF NEW JERSEY.

LOOPER MECHANISM FOR SEWING-MACHINES.

1,128,484.

Specification of Letters Patent. Patented Feb. 16, 1915.

Application filed June 25, 1913. Serial No. 775,638.

To all whom it may concern:

Be it known that I, GEORGE E. MOLYNEUX, citizen of the United States, residing at Bayonne, in the county of Hudson and State of New Jersey, have invented certain new and useful Improvements in Looper Mechanism for Sewing-Machines, of which the following is a specification, reference being had therein to the accompanying drawings.

10 This invention relates to a device for imparting reciprocatory movements to a looper and particularly for producing side-
wise jogging or needle-avoiding movements to a chain-stitch looper whose endwise or
15 loop-seizing and shedding movements are communicated to it by other means.

While the present improvement is adapted for embodiment in different types of sewing machines, it is designed more particularly for use in connection with that class of machines provided with a cylinder bed or work-supporting arm having a longitudinally disposed rock-shaft carrying the looper upon its forward extremity and with-
20 in the outer end of said arm, in which is also journaled a longitudinally arranged shaft from which the looper derives opera-
25 tive movements crosswise of those imparted by its supporting rock-shaft.

30 The present invention has for its object to provide a simple and effective mechanism whereby axial looper jogging movements may be derived from said shaft.

In the preferred form of the improvement, the looper-carrier is pivotally mounted upon a transverse pin of the rock-shaft and carries the usual looper whose blade is disposed crosswise of the rock-shaft. Journaled beneath and parallel with the looper-
35 supporting rock-shaft is a rotary shaft having upon its forward extremity a collar provided with a boss slightly inclined to said shaft and having fitted thereon a loose sleeve adapted to partake of the gyratory or nutatory movements of the said boss while being restrained against rotary move-
40 ment therewith. The sleeve has at one side a ball-socket to receive a ball-stud at one end of a pitman whose opposite end is simi-
45 larly formed and journaled within a ball-socket of an endwise movable rod mounted within a suitable bearing and having a piv-
50 otal and sliding connection with the looper-carrier to impart thereto short rocking movements from which are derived the side-

wise needle-avoiding movement of the looper. Suitable means are provided for oscillating the looper-supporting rock-shaft from which the looper derives its endwise or loop-seizing and shedding movements. 60

The invention will be understood by reference to the accompanying drawings, in which—

Figure 1 is a front end elevation of the work-supporting arm of a cylinder-bed sewing machine with the stitch-forming mechanism, and Fig. 2 a side elevation of the same partly in section. Fig. 3 is a plan of the looper-jogging mechanism, looking upwardly. Fig. 4 is an elevation of the actuating means for the looper-supporting rock-shaft. Figs. 5 and 6 are perspective views of portions of the collar containing the nutatory boss, and Fig. 7 a perspective view of the loose sleeve with the cap separated from the body thereof to expose the ball-socket. 70

The cylinder-bed or work-supporting arm 1 is provided with the throat-plate 2 and the removable end cap 3 housing the looper and its carrier. Mounted axially of the arm 1 in the bearing member 4 thereof, as shown and described more fully in my pending application Serial No. 521,801, filed October 9, 1909, is a longitudinally extending looper rock-shaft 5 having upon its rearward end the crank-arm 6 connected by means of the link 7 with the swinging arm 8 journaled upon the fulcrum-stud 9 which is sustained by a lug 10 upon the inner wall of the frame member 1'. Intermediate its ends the arm 8 is pivotally connected with the lower end of the pitman 11 whose upper end is similarly connected with a lateral arm 12 of a rock-shaft 13 having a second arm 14 to which is pivotally connected the upper end of the pitman 15 whose lower end is formed with a strap 16 embracing an actuating crank 17 of the rotary shaft 18 journaled in the machine frame and extending longitudinally of the work-supporting arm 1 thereof. 85

The looper-supporting rock-shaft has mounted upon its forward end the collar 19 having the reduced portion 20 upon which is mounted by means of the pivotal pin 21 the transversely apertured looper-carrier 22 in the upper portion of which is secured the looper 23 having its blade disposed transversely of the rock-shaft 5 and arranged for coöperation with the needles 24 secured in 110

the clamp 25 of the rectilinearly reciprocating needle-bar 26.

The body of the looper-carrier beneath the fulcrum-pin is provided in its lower portion with a segmental raceway 27 which embraces a split wearing block 28 formed with a spherical socket embracing the head 29 of a ball-stud 30 whose shank is clamped by means of the screw 31 in a vertical socket in the forwardly projecting arm 32 of a split collar 33 clamped by means of a screw 34 upon the reduced forward end of the endwise reciprocating rod or plunger 35 journaled in the tubular bushing 36 of the bearing member 4 beneath the rock-shaft 5. The rearward portion of the rod 35 has a removable cap section 37 secured thereto by means of the screw 38 and having intermediate the two parts a ball-socket 39 open at the rearward end.

Fixed upon the reduced rearward end of the rotary shaft 18 by means of the set-screw 40 is the collar 41 having an inclined forward face from which projects centrally the boss 42 formed with the reduced portion or hub 43 terminating in the pin 44 all disposed upon an axis slightly inclined to that of the collar and its supporting shaft 18. A disk 45 having a reduced portion or hub 46 and provided with a central aperture 47 is adapted to be applied to the central pin 44 and secured to the hub portion 43 of the collar 41 by means of fastening screws 48. The parts 42 and 45 thus secured together constitute a peripherally grooved sectional crank-stud whose axis is inclined to that of said shaft. This crank element has fitted thereon the loose sleeve 49 whose annular tongue 50 is confined within the groove of said crank-stud and between the members 42 and 45 and surrounds the sectional hub afforded by the members 43 and 46. This sleeve has nutatory movements imparted to it by the crank-stud.

45 The loose ring or sleeve 49 has on one side a projection 51 between which and the cap 52 is formed the ball-socket 53 which is open at the forward face of the sleeve and adapted to receive one of the spherical ends of the pitman 54 whose similarly formed opposite end is embraced by the ball-socket 39 of the rod 35. The cap 52 is secured in position by means of screws 55 and 56, the outer extremity of the latter entering a guiding groove 57 provided therefor in the inner wall of the work-supporting arm 1, whereby the sleeve 49 is permitted to perform lateral movements derived from the gyroscopic or nutatory crank element or boss 50 while being restrained against rotation therewith by engagement of the screw 56 with the walls of the groove 57.

By the mechanism above described, edge-wise movements are imparted to the looper-carrier by the operative movements of the

rock-shaft 5 through the transverse pivotal pin 21, thereby communicating to the looper-blade endwise loop-seizing and -shedding movements; while the sidewise or needle-avoiding movements are imparted to the 70 looper-carrier and hence to the looper by the described loose connection between the looper-carrier and the rod 35 which in turn derives its endwise jogging movements from the nutatory movements of the sleeve 49 75 which are resolved through the agency of the link or pitman 54, into the described rectilinear movements.

It is obvious that the present improvement is not limited to the present arrangement of parts, nor to the specific means herein shown and described for producing the nutatory movements communicated in the form of reciprocatory movements to the looper-carrier, nor is the specific means of connection 85 between said nutatory element and the looper-carrier essential to the present improvement.

Having thus set forth the nature of the invention, what I claim herein is:— 90

1. In combination, a looper, a circumnutatory crank element, and a connection between said looper and circumnutatory crank element, comprising a bodily movable link connected with said crank element at a 95 point remote from its center of movement, and means for confining said point of connection always at the same side of the axis of movement of said crank element.

2. In a sewing machine, in combination, a shaft, a looper, a non-rotary nutatory element deriving operative movements from the endwise thrust of said shaft, and a link connected at one end to said nutatory element at one side of its axis of movement 105 and at the other end to said looper.

3. In a sewing machine, in combination, a looper, means for imparting thereto operative movements in one direction, and means for imparting to the looper operative 110 movements in a direction crosswise of the first-named movement, and comprising a non-rotary nutatory element mounted upon said shaft, and a link connected at one end to said nutatory element at one side of its axis of movement and at the other end to said looper.

4. In a sewing machine, in combination, a shaft, a looper, a crank element mounted upon and having an axis inclined to that of said shaft, a non-rotary loose sleeve embracing said crank element, and a connection between the looper and said sleeve including a link having one end connected with the latter at a point eccentric to said 120 crank element.

5. In a sewing machine, in combination, a shaft, a looper, a crank element disposed upon and in inclined relation with said shaft, a loose sleeve fitted to said crank 130

element and provided with a lateral stud, a fixed guideway embracing said stud, and a link having a connection at one end with said looper and at the opposite end with said sleeve.

5 6. In a sewing machine, in combination, a shaft, a looper, a crank element disposed upon and in inclined relation with said shaft, a loose sleeve fitted to said crank element and provided at one side with a ball-socket and with rotation restraining means, an endwise movable plunger-rod operatively connected at one end with said looper and having the opposite end formed 10 with a ball-socket, and a link having spherical ends each embraced by one of said ball-sockets.

15 7. In a sewing machine, in combination, a shaft, a looper, a crank element disposed upon and in inclined relation with said shaft, a loose sleeve fitted to said crank element and provided with a lateral boss and a cap fitted thereto with a divided ball-socket formed between the same, fastening screws 20 for securing said cap in position, one of which projects beyond said cap, a fixed guideway parallel with said shaft and embracing the projecting portion of said fastening screw, an endwise movable plunger-rod operatively connected at one end with 25

said looper and having the opposite end formed with a removable section between which and the adjacent portion of said rod is formed a ball-socket, and a link having said ball-sockets.

35

8. In a sewing machine, in combination, a rock-shaft carrying a transverse fulcrum-spherical ends each embraced by one of pin, a rotary shaft parallel therewith, a looper-carrier mounted upon said fulcrum-pin and provided with a looper, means for actuating said rock-shaft, an endwise movable plunger-rod parallel with said rock-shaft, an operative connection between said plunger-rod and the looper-carrier for imparting to the latter tilting movements upon said fulcrum-pin, a crank element mounted upon and inclined to said rotary shaft, a sleeve embracing and deriving nutatory movements from said crank element and 40 provided with rotation-restraining means, and a link connection between said sleeve and the plunger-rod.

45 In testimony whereof, I have signed my name to this specification, in the presence 50 of two subscribing witnesses.

GEORGE E. MOLYNEUX.
